United States Patent Office

Des. 204,988
Patented June 7, 1966

204,988

CHRISTMAS ORNAMENT OR SIMILAR ARTICLE

Jack Burnbaum, Newton, Mass., assignor of one-half to Arnold L. Frank, Newton, Mass.

Filed Sept. 30, 1965, Ser. No. 87,229

Term of patent 14 years

(Cl. D29—1)

Fig. 1.

Fig. 2.

Fig.3.

Fig.4.

Fig.5.

FIG. 1 is a front elevational view of a Christmas ornament showing my new design;

FIG. 2 is a top plan view;

FIG. 3 is a side elevational view taken at a right angle to FIG. 1, the side opposite thereto being similar in appearance;

FIG. 4 is a bottom plan view, and

FIG. 5 is a rear elevational view.

I claim:

The ornamental design for a Christmas ornament or similar article, substantially as shown and described.
